Des. 185,901
Patented Aug. 18, 1959

185,901

GOLFING VEHICLE OR THE LIKE

John T. Parrett, Benton Harbor, Mich.

Application February 9, 1959, Serial No. 54,519

Term of patent 7 years

(Cl. D14—3)

Fig. 1

Fig. 2

Fig. 3

FIG. 4

FIG. 5

Fig. 1 is a perspective view of a golfing vehicle or the like embodying my new design;

Fig. 2 is a front elevational view thereof;

Fig. 3 is a rear elevational view thereof;

Fig. 4 is a top plan view thereof; and

Fig. 5 is a side elevational view thereof.

I claim the ornamental design for a golfing vehicle or the like, as shown.
